CLAIM

The ornamental design for a display screen or portion thereof with an animated graphical user interface, as shown and described.

DESCRIPTION

FIG. 1 is a front view of a first image in a sequence for a first embodiment of a display screen or portion thereof with an animated graphical user interface;

FIG. 2 is a front view of a second image thereof;
FIG. 3 is a front view of a third image thereof;
FIG. 4 is a front view of a fourth image thereof;
FIG. 5 is a front view of a fifth image thereof;
FIG. 6 is a front view of a sixth image thereof;
FIG. 7 is a front view of a seventh image thereof;
FIG. 8 is a front view of an eighth image thereof;
FIG. 9 is a front view of a first image in a sequence for a second embodiment of a display screen or portion thereof with an animated graphical user interface;
FIG. 10 is a front view of a second image thereof;
FIG. 11 is a front view of a third image thereof;
FIG. 12 is a front view of a fourth image thereof;
FIG. 13 is a front view of a fifth image thereof;
FIG. 14 is a front view of a sixth image thereof;
FIG. 15 is a front view of a seventh image thereof;
FIG. 16 is a front view of an eighth image thereof;
FIG. 17 is a front view of a first image in a sequence for a third embodiment of a display screen or portion thereof with an animated graphical user interface;
FIG. 18 is a front view of a second image thereof;
FIG. 19 is a front view of a third image thereof;
FIG. 20 is a front view of a fourth image thereof;
FIG. 21 is a front view of a fifth image thereof;
FIG. 22 is a front view of a sixth image thereof;
FIG. 23 is a front view of a seventh image thereof; and,
FIG. 24 is a front view of an eighth image thereof.

The appearance of the animated graphical user interface sequentially transitions between the images shown in FIGS. 1-8, in FIGS. 9-16, and in FIGS. 17-24. The process or period in which an image transitions into another image forms no part of the claimed design.

The broken line showing of the display screen or portion thereof and graphical user interface depict portions of the article that form no part of the claimed design.
